STERLING H. CAMPBELL, OF ST. LOUIS, MISSOURI.

COUPLING-RELEASE RIGGING.

1,396,726.

Specification of Letters Patent. Patented Nov. 15, 1921.

Application filed April 6, 1921. Serial No. 458,890.

To all whom it may concern:

Be it known that I, STERLING H. CAMPBELL, a citizen of the United States of America, residing at the city of St. Louis, 5 State of Missouri, United States of America, have invented a certain new and useful Coupling-Release Rigging, of which the following is such a full, clear, and exact description as will enable any one skilled in 10 the art to which it appertains to make and use the same, reference being had to the accompanying drawings, forming part of this specification.

The object of my invention is to produce 15 a coupler release rigging, of the type employing an operating rock shaft, which will be as simple as possible in construction and at the same time reliable in operation and not likely to get out of order. 20 In the accompanying drawings which illustrate one form of device made in accordance with my invention together with a portion of a railway car to which it is applied, Figure 1 is a top plan view, Fig. 2 is an enlarged end view of a portion of the device, 25 Fig. 3 is a front view of the parts shown in Fig. 2 and Fig. 4 is a front view of the parts shown in Fig. 1.

5 indicates a railway car provided with 30 a draw head 6 having the usual locking pin 7. In the locking pin 7 is a horizontal eye for engagement with the operating connection. 9 is a rock shaft forming the operating rod of the device and secured to the car 35 5 by means of brackets 10 and 11, the bracket 10 being positioned adjacent to the handle end of the rod 9 and the bracket 11 at the opposite or inner end of said rod. 12 is the operating arm arranged at right angles to 40 the rod 9 at the inner end thereof. 13 is the operating handle carried at the outer end of the rod 9 and arranged at right angles thereto and preferably at right angles to a plane passing through the arm 12. The 45 outer end of the operating arm 12 is provided with a horizontal eye 14. 15 is a member forming the connection between the operating arm 12 and the locking pin 7. The upper end 16 of the member 15 is bent over 50 at right angles to the body of said member so as to form a pivot or trunnion passing through the horizontal opening 14 in the rod 12. The end 16 is threaded to engage with a nut 17 and is provided with a slot 18 55 so that after the nut 17 is in position the end of the member may be spread to prevent

the disengagement of said nut. The lower end of the member 15 is bent to form an enlarged loop 19 closed at both ends but having an opening 20 in the upper side to 60 allow its engagement with the eye 8 of the locking pin 7.

In applying my device to a car the elongated loop 19 is first engaged with the eye 8 of the locking pin which is accomplished 65 by means of the opening 20, after which the end 16 is passed through the opening 14. The nut 17 is now placed in position and the end 16 spread by inserting any suitable tool in the slot 18. The elongated form of 70 the loop will allow the necessary lateral movement between the operating rod 12 and the coupler head 6 while the rocking movement in a vertical longitudinal plane will allow for the necessary longitudinal movement between the said parts. It will be noted that the arm 12 when in its normal position is slightly inclined upwardly as shown in Fig. 2 and that the handle 13 has a corresponding inclination to the perpendicular so that when the end rod of the arm 12 is drawn downwardly by the relative longitudinal movement between the rod and coupler while the train is in motion, the handle 13 will not be thrown into contact 85 with the end of the car.

Having fully described my invention, what I claim as new and desire to secure by Letters Patent of the United States is:

1. In a device of the class described, the 90 combination with a car having a vertical plane coupler head provided with a locking pin, of a rock shaft carrying an integral operating arm provided with a horizontal eye formed in an integral portion of the arm, 95 and a rigid connecting member pivoted in said eye to move only in a vertical plane in the direction of the length of the coupler, said member having an elongated open sided loop engaging with the eye of the coupler locking 100 pin to allow lateral movement of the coupler head.

2. In a device of the class described, the 105 combination with a car having a vertical plane coupler head provided with a locking pin, of a rock shaft carrying an integral operating arm provided with a horizontal eye formed in an integral portion of the arm, and a rigid connecting member comprising a vertical rod having a lateral projection at its 110 upper end extending through said eye so as to move only in a vertical plane in the direc-

tion of the length of the coupler, an elongated loop at its lower end engaging with the eye of the coupler locking pin, and retaining means for said member carried by 5 said projection.

3. In a device of the class described, the combination with a car having a vertical plane coupler head provided with a locking pin, of a rock shaft, an operating arm carried by said rock shaft and normally in-

clined upward therefrom, an operating handle also carried by said rock shaft and normally inclined from the perpendicular, and a rigid connecting member having a fixed pivotal connection with said operating 15 arm, and a laterally sliding connection with the coupler locking pin.

In testimony whereof, I have hereunto set my hand and affixed my seal.

STERLING H. CAMPBELL. [L.S.]
